UNITED STATES PATENT OFFICE.

EUGEN TÜRCK, OF BARMEN, GERMANY.

MANUFACTURE OF MACHINE-BRAIDED LACE.

Application filed April 1, 1925, Serial No. 19,777, and in Germany April 11, 1924.

The present invention has reference to improvements in the manufacture of lace on the single thread Malhère braiding machine described in the U. S. Patent No. 613,380, 5 in which a lace web is continuously formed in tubular shape about a stationary mandrel, and is subsequently drawn off the mandrel and opened out flat. In the prior art the closed lace tube or hose was formed by uniting the longitudinal opposed fabric edges by means of auxiliary interwoven threads, which later, for the purpose of opening up the tube, had to be cut and then withdrawn, which procedure wasted time and material. 10 In the later art it was proposed to do away with these edge-connecting auxiliary threads by guiding the fabric edges on wire members and running one or more steady threads in zig-zag fashion over these wire guides, as described for instance in the U. S. Patent No. 1,024,247. When the lace tube thus formed was drawn off the mandrel, these steady threads, which were not embodied in any way in the lace structure proper, 15 readily slipped off the wire guides along with the lace edges, and were then recovered for repeated use, and the lace tube was then automatically opened in well known manner and laid out flat. In practical operation this procedure, however, was found defective for various reasons, mainly because it did not prevent, as was hoped, the deformation of the web fabric upon the latter being drawn off the mandrel. 20 In my endeavors to remedy this serious drawback I found that this distortion and deformation of the web structure is due to the relative arrangement and action of the two drawing-off rollers of the old art, which are positioned at opposite sides of the **S** portion of the mandrel horizontally one behind the other, so that the web is unevenly seized on opposite sides and is unevenly stressed and pulled out of shape. 25 According to the present invention this defect is effectively obviated by guiding and temporarily uniting the longitudinal opposed edges of the web during and for a short period after the formation of the latter on stationary guide means, if desired with the aid of one or more auxiliary threads, and by then seizing the web tube and drawing it off the mandrel by means of two horizontally aligned draw-off rollers, which are caused to pullingly act on opposite sides of the web 30 tube close above its formative zone. How this web feeding action is brought about is immaterial as long as it acts on the web practically all around the web circumference at the same level. The mandrel is relatively short, and presents a cylindrical body portion and a flattened end or delivery portion, formed by two flattened faces of a curvature to conform to the circumference of the respectively cooperating draw-off rollers, as clearly shown in Fig. 1. The two rollers operating on the flattened web portion from opposite sides seize the fabric evenly practically all around its circumference and prevent thereby one-sided stress and undue distortion and deformation thereof. During the drawing-off step the longitudinal web edges automatically slide off the guide means, whereupon the web tube is opened out flat 35 in the well known manner. 75

The use of the auxiliary threads can also be dispensed with entirely by providing only a single guide element for temporarily unitedly guiding the longitudinal edges of the forming web tube. 80

The accompanying drawing illustrates by way of example apparatus for carrying out the new method, in which drawing:—

Fig. 1 is a side-elevation, partly in section, of the thread collector and draw-off mechanism, and 85

Fig. 2 is a plan view, partly in section on the line 2—2 in Fig. 1. 90

Referring to the drawing, *b* indicates the closed ring collector in which the braiding threads unwinding from bobbins (not shown, run together and at the lower edge of which the web is formed. As usual the collector *b* surrounds a stationary mandrel *c* while leaving therebetween a passage for the web *a*, which mandrel at its lower portion has a circular cross-section whereas, at its upper portion, it has a flat, rectangular cross-section. Upon this mandrel the web *a* is formed in well known manner. According to the present invention, the web is obtained in tubular form by guiding the two longitudinal edges of the web on a single common guiding member *d*, the lower end of which is rigidly secured to the machine, and the upper end of which freely extends up through the collector ring *b*. The longitudinal edges of the web are guided on the guide member for example by loops *a'* of one edge and loops *a''* of the other being so 100 105 110

alternately guided on the wire that the latter holds the web together in tubular form, while said guide member owing to its being embraced alternately by the edge-loops of the web is so supported that there can be no lateral yield.

The web is drawn up upwardly by the draw off rollers h, h the edge-loops a', a' being successively stripped from the member d and the tube so opened.

In order that there may be no deformation of the web, according to the present invention, two draw-off rollers h, h are arranged on opposite sides of the mandrel, which is flattened off at its upper portion, and are positioned opposite to each other at the same level, these rollers being situated as closely as possible over the collector-ring b so that, immediately after leaving the latter, the web surrounding the mandrel is gripped simultaneously on two opposite sides and consequently on its full or approximately full width by the two rollers, and is in this way drawn off upwardly perfectly uniformly. In comparison with known mandrels the mandrel c is considerable shortened and its tapering faces are curved to correspond with the operative contour of the peripheral faces of the draw-off rollers h, h . Its terminal rectangularly flattened portion is preferably curved above the draw-off rollers h, h , to overhang one of the rollers.

The guide member d is conveniently arranged in the middle plane between the two rollers h, h so that it is located at one of the narrow sides of the flattened portion of the mandrel. Consequently the guide wire can extend into the intermediate space between the two draw-off rollers h, h , so that the web when it is grasped and advanced by the rollers is still held together in the tubular form by the wire d , and consequently is positively guided at its longitudinal edges, this completely obviating deformation.

Claims.

1. The described method of producing flat lace by the single thread Malhère braiding machine, which consists in braidingly forming a longitudinally split web tube, in seizing and taking off this tube close above its formative zone simultaneously at circumferential points all equidistantly spaced from the formative zone, in guiding the web edges during the travel of the tube from its forma-

tive zone to the take-off zone, and in releasing them at the latter zone.

2. The described method of producing flat lace by the single thread Malhère braiding machine, which consists in braidingly forming a longitudinally split web tube, in seizing and taking off this tube close above its formative zone simultaneously at circumferential points all equidistantly spaced from the formative zone, in unitingly guiding the web edges during the travel of the tube from its formative zone to the take-off zone, and disuniting and releasing them at the latter zone, and in tensioning the temporarily closed tube during its passage between these two zones.

3. Apparatus for carrying out the described method of producing flat lace, comprising in combination with the mandrel forming the tubular web, a pair of take-up rollers mounted relatively closely above the web forming zone, and stationary guide means terminating close to said rollers for temporarily guiding the longitudinal edges of the web from the formative zone of the web to its take-off zone.

4. Apparatus for carrying out the described method of producing flat lace, comprising in combination with the mandrel forming the web tube, a pair of take-up rollers mounted relatively closely above the web forming zone, and stationary guide means terminating in close relation to said rollers for temporarily unitedly guiding the longitudinal web edges from the formative zone of the web to its take-off zone, the upper portion of the mandrel being concavely flattened to conform to the cooperating circumference of said rollers.

5. Apparatus for carrying out the described method of producing machine-braided lace on a single thread machine, comprising in combination, a web-forming mandrel, presenting a cylindrical body portion and a tapering head portion, a pair of take-up rollers mounted one on each side of said mandrel close above the web-forming zone, and a stationary guide member arranged longitudinally of the mandrel in its middle plane and extending along one of its narrow head edges up between the said two rollers for temporarily guiding the longitudinal edges of the web from the point of its formation to the take-off point.

In testimony whereof I affix my signature.
EUGEN TURCK.
